DESIGN FOR A HOUSING FOR A FLOOR TREATING MACHINE

Carl G. Wennerstrom, Evanston, Ill., assignor to
Universal Gear Corporation, Indianapolis, Ind.,
a corporation of Delaware

Application October 26, 1933, Serial No. 49,557

Term of patent 14 years

To all whom it may concern:

Be it known that I, CARL G. WENNERSTROM, a citizen of the United States, residing in Evanston, Cook County, Illinois, have invented a new, original, and ornamental Design for a Housing for a Floor Treating Machine, of which the following is a specification, reference being had to the accompanying drawing, forming a part hereof.

The figure is a perspective view of a housing for a floor treating machine showing my new design. The floor treating machines in connec-

tion with which my said design was invented are floor scrubbers, floor cutters and grinders and floor polishers. The scrubbing, cutting, grinding or polishing element forming a part of such machines is not shown in the drawing, but normally projects below the lower edge of the housing.

I claim:—

The ornamental design for a housing for a floor treating machine substantially as shown and described.

CARL G. WENNERSTROM.
